UNITED STATES PATENT OFFICE.

THOMAS W. ELDER, JR., OF BROOKLYN, NEW YORK, ASSIGNOR TO AMERICAN CAR AND FOUNDRY COMPANY, OF NEW YORK, N. Y., A CORPORATION OF NEW JERSEY.

CAR-DOOR LOCK.

Application filed July 28, 1926. Serial No. 125,463.

In the drawings:

Fig. 1 is a partial side view of a cane car with my invention applied thereto;

Fig. 2 shows a vertical transverse section 5 through one of the door locks shown in Fig. 1, on a larger scale, taken as indicated by the line 2—2 in Fig. 3;

Fig. 3 is a side view of one of the door locks, similar to that afforded by Fig. 1, but 10 on a larger scale;

Fig. 4 is a plan view of the lock;

Fig. 5 is a fragmentary cross-sectional view similar to Fig. 2, but showing a somewhat different construction;

15 Fig. 6 is a side view similar to Fig. 3, but illustrating the locking mechanism of Fig. 5.

My invention relates to door locks, suitable 20 for railway car doors and the like, and especially useful for doors of general utility cars, cane cars, etc. I aim to provide a simple, rugged and effective lock; easy and inexpensive to manufacture and install; secure in action; convenient and quick in operation. I also aim to make the mechanism 25 positively or irreversibly self-locking, so that dependence need not be placed on the operating device or mechanism to resist the tendency of the load pressure against the door to open it; also, to obviate or minimize torsional stresses on the mechanism when the 30 door is locked.

Fig. 1 shows a cane car of usual type with side doors 9, 10 of open work construction. The door 9 comprises a series of upright 35 angle bars 11 having their upper ends hinged or pivoted at 12 to a longitudinal top rail 13, and secured at their lower ends to the inner side of a longitudinal lower rail 14 of angle section. Near their upper ends, the 40 uprights 11 are also secured to a longitudinal angle bar 15. The door 9 as a whole is braced by a diagonal angle bar 16 secured to the uprights 11. The door 9 swings outward to open, while in closing its lower portion seats laterally against the floor structure 45 of the car or its side sill 18 (Figs. 1 and 2).

For holding the door 9 shut, there are shown a plurality of "crank" locks 19, mounted at intervals along the side sill 18, 50 in position to engage the lower portion of the door. As shown in Figs. 1-4, the locks 19 are operated by a common rotatable shaft or rod 20 extending along the lower edge of the door 9, and the locking cranks (one for 55 each lock 19) are provided by offsetting this

rod. When the rod 20 is turned, one of its relatively offset portions 21, 22 moves or shifts into and out of locking position in front of the door 9, and vice-versa. The other such portions are mounted in suitable 60 supporting means carried by the sill 18. Such a rod 20 with one or more locking cranks may conveniently be termed a "snake rod." In the present instance, it is the shorter offset portions 21 that lock the door 65 in this manner by coming in front of and engaging the lower flanges of angle clips 23 (one for each lock 19) riveted to the bottom rail 14 of the door. The longer or "main" portions 22 of the rod are mounted in supporting brackets 24 whose feet are riveted, in the present instance, to the upper flange 70 and to the vertical web of the side sill 18. As here shown, these supporting brackets 24 are arranged at either side of each of the 75 locking cranks 21.

As shown in Figs. 2 and 3, the bracket support 24 has the form of a sheet metal strip or strap extending outward from the sill 18 substantially horizontally, curved 80 downward in an arc 25 such as described by a main portion 22 of the rod 20 when revolving about the crank portion 21 as hereinafter described, and at the lower end of its arcuate portion bent first upward at 26 and 85 then downward,—S-fashion. Webs 27 connect the edges of the strap across its final bend, to brace and reinforce this portion of the bracket against impact of the main portion 22 of the rod 20 at the limit of its (unlocking) downward movement. The bends of the strap at the upper and lower extremities of its arc 25 have substantially the same curvature as the surface of the rod 20 itself, so that the latter may seat snugly and stably 95 in them. At the inner (sill) side of the sphere of movement determined for the cranks 21 by the main rod portions 22 and the brackets 24, fulcrum supports or seats are provided for the cranks 21, in the present instance by turning or bending outward 100 the lower flanges of the angle clips 23 at 28 (Fig. 2), preferably with a curvature corresponding to the surface of the rod 20.

For turning the rod 20, a crank arm 30 105 may be provided at the end of the car, as by bending the corresponding end of the rod 20 at right angles as shown in Fig. 1. This crank 30 may conveniently bear such angular relation to the locking mechanism that when 110

the door 9 is locked, the crank 30 is turned upright against the end post 31 of the super-structure of the car (Fig. 2, dot and dash position), while when the door is unlocked, the 5 crank 30 hangs down against the sill 18 (Fig. 2, triple dot and dash position). The crank 30 may conveniently be secured in its upper (locked) position by means of a ring or link 32 slidable on a bracket 33 secured 10 to the post 31, so that it may be lifted over the end of the crank to free the latter for operation.

When the door is unlocked, the main portion 22 of the rod 20 lies in the lower seat 15 of the bracket seat 26 with the crank 30 extending downward (as already mentioned) and the crank 21 extending outward,—as shown in dash and triple dot lines in Fig. 2. When, however, the crank 30 and the 20 rod 20 are rotated clockwise (speaking with reference to Fig. 2), the rod shifts sidewise upward or “climbs” into the locked position shown in full lines in Fig. 2, with the crank 21 against and in front of the lower angle 25 flange 23 on its seat 28 and the main portion 22 of the rod seated in the curved corner at the upper end of the bracket arc 25. As the rod 20 turns clockwise from the unlocked position, the first action is to swing the 25 crank 21 upward about the main portion 22 as a substantially fixed axis, along the arc indicated in dash and triple dot lines in Fig. 2. This movement is limited and terminated, however, by striking of the crank 21 against 30 the angle 23, on the outward projecting seat or fulcrum portion 28 of the latter. Further clockwise rotation of the rod 20 then causes its main portion 22 to swing bodily upward and inward on the crank 21 as a substantially fixed axis, along the arc shown in dash and dot lines in Fig. 2. In this latter movement, the main portion 22 of the rod 20 is guided by the arcuate outer portion 25 of the bracket 24. Accordingly, the final position 35 of the rod 22 is in the top of the bracket 24, as shown in full lines in Fig. 2, with the crank 21 still seated and engaged against the angle 20 and extending obliquely outward and upward therefrom to the main 40 portion 22, which is seated at the upper end of the arcuate portion,—the crank 30 extending as indicated in dot and dash lines. In this position, it will be seen, the crank 21 is stable as against the force exerted on it by any opening tendency of the door 9, since, 45 it lies slightly below “dead center” with reference to the effective thrust of the door against it. Hence such thrust merely tends to bend the crank 21 and to exert a compressive stress on the oblique portions of the 50 rod 20 that connect the relatively offset portions, without any tendency to rotate the rod 20 counter-clockwise and unlock the door. On the contrary, the tendency of such thrust 55 is to hold the rod 20 fast in locking posi-

tion. The door 9 may be unlocked by a simple reversal of the locking movement.

As shown in Fig. 1, the door 10 and its locking mechanism are similarly constructed and arranged, except that the door 10 extends 70 lower and its shaft 20^a and brackets 24^a, etc., are mounted at a lower position on the side sill 18, so that the shaft 20^a may extend along below the parts 20, 24 for the door 9 to the same end post 31 from which the door 9 is 75 controlled. Preferably, a bracket support 80 may be provided for the ends of both shafts 20 and 20^a near the end post 31, apertured to accommodate their opening and closing movements as above described.

The construction shown in Figs. 5 and 6 differs from that of Figs. 1 to 4 in that the seat or fulcrum for the crank 21 is not formed on the lower flange of the angle 23, as in Fig. 2, but by an angle bracket 35 85 riveted to the web of the sill 18 and projecting outward just below the lower edge of the angle 23, in position to limit the closing movement of the crank 21 and seat the latter in the same way as does the part 28 in 90 Fig. 2. Also, the upper portion of the bracket 24^b slopes downward slightly from the top of the sill 18, and the lower portion of the bracket extends horizontally inward (without the S-bend 26 of Fig. 2) and is 95 supplemented with a bent metal strip bracket 36 riveted under the lower foot of the bracket 24^b and bent outward and upward to limit inward movement of the rod 22, so as to arrest and seat it at the lower end 100 of the arcuate portion 25 of the bracket 24^b as before. Also, the car floor (of sheet metal rather than of plank) is interposed between the upper flange of the sill 18 and the upper end or foot of the bracket 24, instead of 105 overlying said foot, as in Fig. 2.

In Figs. 5 and 6, various parts and features are marked with the same reference characters as in Figs. 1-4, as a means of dispensing with repetitive descriptions. 110

What is claimed is:

1. A door lock of the character described comprising a rotary crank rod with an offset portion or crank shiftable into a stable locking position, beyond dead center, in front of the door, or out of the way of the door to permit the same to open past the rod, with means for limiting locking movement of the rod to said locking position; so that opening pressure on the door shall act to maintain 115 the rod in said locking position.

2. A door lock of the character described comprising a rotary crank rod, with portions offset laterally relative to one another, and means cooperating with said relatively offset portions to shift the rotating rod sideways between an unlocked position where the door may open past it and a locking position 125 in front of the door.

3. A door lock of the character described 130

comprising a rotary crank rod, with portions offset laterally relative to one another; an enclosing guide for one of said relatively offset portions; and a fulcrum for the other of said portions extending into the sphere of movement determined for the latter portion by the guide; said parts being so correlated and arranged that rotation of the rod will cause it to shift laterally between an unlocked position where the door may open past it and a locking position in front of the door.

4. A door lock of the character described comprising a rotary crank rod, with portions offset laterally relative to one another, extending along the lower edge of the door to be secured, and means cooperating with the relatively offset portions of the rotating rod to enable the latter to climb from a position below the door edge to a position in front of the door.

5. A door lock of the character described comprising a rotary crank rod, with portions offset laterally relative to one another, extending along the lower edge of the door to be secured; an enclosing guide support for one of the relatively offset portions of the rod; and a fulcrum support for the other of said portions extending into the sphere of movement determined for the latter portion by said guide support; said parts being so correlated and arranged that the rotating rod may climb upon the fulcrum support

from a position below the door edge to a position in front of the door.

6. A door lock of the character described comprising a rotary crank rod, with portions offset laterally relative to one another; and means cooperating with said relatively offset portions to shift the rotating rod laterally between an unlocked position, where the door may open past the rod, and a stable locking position in front of the door, with the crank formed by one of said offset portions beyond dead center, and to limit the locking movement of the rod to said stable locking position.

7. A door lock of the character described comprising a rotary crank rod, with portions offset laterally relative to one another, extending along the lower edge of the door to be secured; an enclosing guide support for one of the relatively offset portions of the rod; and a fulcrum support for the other of said portions extending into the sphere of movement determined for the latter portion by said guide support; said parts being so correlated and arranged that the rotating rod may climb upon the fulcrum support from a position below the door edge to a limiting stable locking position in front of the door, with the crank formed by one of said offset portions beyond dead center.

In witness whereof I have hereunto set my hand.

THOMAS W. ELDER, JR.
